MOLDED KEY CAP FOR WRITING MACHINES

Gerald K. Geerlings, New Canaan, Conn., assignor
to Remington Rand Inc., New York, N. Y., a
corporation of Delaware

Application April 7, 1949, Serial No. 85,993

2 Claims. (Cl. 197—102)

1

The present invention relates to key caps particularly adapted for use on typewriters and other writing machines and particularly to a key cap molded from suitable plastic material.

The present invention provides a key cap wherein the top and side portions have rounded surfaces merging one into the other to eliminate all sharp corners and to provide an upper surface having a concave depression in the central portion surrounded on the sides and at the rear by a rounded ridge portion with the depression opening at the front of the key, the shape being formed to conform with the shape of the end portion of a person's finger used to engage the upper key surface. The cap is molded to provide front, side and rear wall portions extending below the top portion of the key with the front wall portion extending about twice as far below the top wall of the key as the rear wall. This provides for cooperation between the several wall portions depending from the top wall to obtain a molded plastic cap having substantial strength with a central partition structure formed with a socket to receive the end of a key shank and at the same time providing a cap having a new and pleasing appearance.

According to the present invention errors in typing due to overshooting the key, striking the key short, or striking it to the left or right will be materially reduced by reason of the finger fitting depression in the top portion of the key forming a self-centering feature that will aid an operator in properly centering the fingers on each key on a typewriter keyboard or the like. The arrangement of the key top surface with rounded corners and an open front into the concave depression will reduce fatigue in typing due to the finger fitting shape of the key top as compared with many previous forms of key tops that do not fit the shape of the finger and have a ridge at the front portion.

In the drawing:

Fig. 1 shows a key cap constructed according to the invention in front elevation.

Fig. 2 is a plan view of the key cap.

Fig. 3 is a side elevation looking at the left-hand side of the key cap.

Fig. 4 is a vertical cross-section taken on line 4—4 of Fig. 1.

Fig. 5 is a rear elevation of the key cap.

Fig. 6 is a bottom plan view.

The molded key cap constructed according to the invention is preferably made of a suitable plastic material molded in one piece. The key cap has a top wall 1, front wall 2, side walls 3,

and rear wall 4. The front, side, and rear walls are in depending relation from the margins of top wall 1. The rear wall has a length equal to about half of the length of front wall 2 in depending relation below top wall 1. The outer surfaces of the front, side, and rear walls where they are joined together at the corners of the key cap are rounded as indicated at 5 to provide smooth continuous outer surfaces in which one wall extending laterally to another is curved at the corner to merge into the laterally extending wall portion.

The bottom edges of the rear, side, and front walls have a curved form extending from the rear surface of rear wall 4 in downwardly curving and forwardly extending relation, as indicated at 6 in Figs. 3 and 4, inclining downwardly toward and to the front surface of front wall 2.

A transverse central partition 7 is formed in depending relation from top wall 1 and extends between the central portions of front wall 2 and rear wall 4 to provide a rigid key cap structure. The central portion of partition 7 is formed with a vertically extending socket 8 below top wall 1 for slidably receiving the upwardly extending end of a key shank on a typewriter key or other similar writing machine key in tightly fitting frictional relation.

On opposite sides of central partition 7 the body of the key below top wall 1 is hollow within front, side, and rear walls 2, 3, and 4, respectively, the open compartments between the front, side, and rear walls being open at the bottom of the key cap.

Top wall 1 is formed with a concave depression 9 extending throughout the portions of the top wall within the side and rear margins thereof, the curvature and size of the depression being of a shape to fit the pad on the end of the average human finger. Depression 9 extends through to the front edge of the key cap where the top wall is rounded in downwardly extending relation so that the outer surface will merge into the front surface of front wall 2 as indicated at 10 in Fig. 4.

The side and rear margins of top wall 1 are formed with a ridge 11 having a convex rounded form with the surface of concave depression 9 extending upwardly and merging into the convex surface of ridge 11. The convex surface of ridge 11 extends outwardly and curves downwardly to merge into the outer surfaces of side walls 3 and rear wall 4 with the corner portions rounded in conformity with rounded corners 5 at the rear corners of the key cap. The formation of ridge 11 around the sides and rear of

the key and the rounded convex surface thereof merges into the concave surface of depression 9 to provide a composite shape on top wall 1 in which the central portion of the key with its finger conforming shape and the depression open at the front of the key fits one's finger so it may freely project into the depression in horizontal relation without obstruction from the front portion of the key cap.

When a plurality of keys constructed as illustrated in the drawing and above described, are used on a typewriter keyboard in rows one behind the other with the keys in each row slightly above the forward row, the long front wall 2 depending below top wall 1 in a row to the rear and elevated above a preceding row will provide a key cap arrangement where the caps on adjacent keys in the row are relatively close together and have the lower end of the front wall of each key cap extending below the top wall of the key cap in a preceding row.

The key cap made according to this invention when placed on a plurality of rows of keys will have the side walls and front and rear walls in adjacent but closely spaced relation to the corresponding walls of adjacent rows of keys and adjacent key caps in a row, to substantially close the space in the keyboard portion of the machine to an extent sufficient to prevent an operator's fingers from slipping off one key into the space between two keys while the shape of the key cap of the present invention will also aid in guiding a finger into the center portion of a key cap where it is not properly aligned therewith.

In using the key cap of the present invention, an operator in striking a key applies the end pad portion of the finger to the top of the key cap. In moving the finger onto the key cap, the pad portion at the lower front end of the finger in horizontal position can be moved into the concave depression 9 from the front of the key without difficulty and with a free movement in view of the fact that the front part of the key top is at the same level as the middle part of the key top in addition to having the front edge rounded downwardly and merging into front wall 2. The ridge portion 11 around the sides and rear part of the key helps an operator to properly center the finger on the key cap by the sense of touch in movement to engage the key cap for operating a key. The ridge portion 11 at the rear of the key cap operates effectively to limit rearward movement of the operator's finger on the key cap to prevent the common fault experienced with previous forms of key caps of the operator's fingers overshooting the key cap to too great an extent and thereby interfering with the key caps on keys to the rear of the one which it is desired to operate. This has resulted in breaking finger nails. With the rounded upper margins and corners on the key cap the finger nails of an operator will not catch on any of the key caps, will be limited by front walls 2 of rearwardly located key caps and will not slip between adjacent key caps constructed and mounted in a keyboard according to the invention. With the side portions of the key cap sloping from ridge portion 11 toward the center an oper-

ator will be aided in centering a finger on a key cap with the downward slope at the sides of the key cap tending to cause a finger pad to slide toward the center. An operator will not have an impression left in the finger where it passes over

the front end of the key caps made according to the present invention in comparison with previous types of keys having ridges across the front. In addition, fatigue in operating a machine equipped with key caps according to the present invention will be greatly reduced and the appearance of the machine will be greatly enhanced.

The invention claimed is:

1. A key cap for typewriting and similar machines, comprising a molded body having integral side, front, top and rear walls, and a central transverse wall extending between the front and rear walls, depending from said top wall and formed with a socket for slidably receiving the end of a key-lever, said top wall having a ridge extending along the side and rear edges and having a central valley portion extending throughout the central portion of said top wall within said ridge and open at the front of said cap, said front wall depending substantially twice as far as said rear wall below said top wall, said side walls having curved lower edges extending from said rear wall to the lower edge of said front wall, said ridge and valley portion of said top wall having curved surfaces merging into one another and said top wall having a downwardly curved surface across the front merging into the front wall.

2. A key cap for writing machines, comprising a molded body having imperforate top, side, front and rear walls, said front and rear walls depending respectively from the front and rear portions of said top wall and said front wall having a depending length approximately twice that of the rear wall, the side walls, front and rear walls having the lower edge curved downwardly from the rear face of the rear wall in inclined relation to the top wall toward and to the front face of the front wall, said rear, side and front walls having rounded outer corner surfaces, said top wall having a concave central depression in the upper face bounded by a convexly rounded ridge along the side and rear portions, said top wall having the upper surface in the central depression merging into a rounded front surface curving into the front surface of the front wall, and a central transverse vertical partition integral with the front and rear walls and depending from the top wall, said partition having a key-shank receiving socket formed therein open at the lower edge.
